UNITED STATES PATENT OFFICE.

JOHN M. DOPPEL, OF NEW YORK, N. Y.

REFRIGERATOR.

SPECIFICATION forming part of Letters Patent No. 756,004, dated March 29, 1904.

Application filed March 5, 1903. Serial No. 146,355. (No model.)

To all whom it may concern:

Be it known that I, JOHN M. DOPPEL, a citizen of the United States, and a resident of the city of New York, borough of Brooklyn, in the county of Kings and State of New York, have invented a new and useful Improvement in Refrigerators, of which the following is a full, clear, and exact description.

My invention relates to the construction of refrigerators in which receptacles containing ice-cream are to be stored or from which the cream is served.

The purpose of the invention is to so construct the refrigerator that while it is packed with a non-heat-conducting material a perfect circulation of air will be obtained practically around both sides of the packed section, to which end air-ventilating spaces or chambers are located between the packed section and the inner box or receiving section and the said packed section and the outer box or casing section, which air spaces or chambers have suitable connection with the outside atmosphere.

Another purpose of the invention is to utilize the inner-ventilating or air space as a conductor for the products of evaporation or condensation and direct the said products to a chamber below the inner box or receiving section and to provide the said lower chamber with a waterproof lining and an outlet adapted for connection with an offtake and also to provide the inner box or receiving section with a fluid-conducting device in operative connection with the said offtake for the outer or casing section.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in both figures.

Figure 1 is a sectional perspective view of a refrigerator constructed in accordance with my invention, and Fig. 2 is a transverse section through the refrigerator.

The side and bottom portions of the refrigerator are preferably made of soft wood, par-

tially of clear white pine and partially of spruce, for example, while the top portion of the refrigerator is preferably constructed of a hard wood. The refrigerator is practically rectangular and may be of any desired width and length.

In the construction of the body portion of the refrigerator an outer box-casing section A is employed, including end, front, and back members, together with a bottom member 60 suitably joined and a correspondingly-formed inner or receiving box section B of less dimensions than the outer or casing section A; but the upper edge of the inner box or receiving section B is practically flush with the corresponding portion of the outer or casing section A. Thus it will be observed that a space is provided between the front and rear and end portions of the two box-sections, and likewise a space is formed between the bottom of the two sections A and B, the latter space being adapted as a moisture-collecting chamber 15, to be hereinafter more particularly referred to. The space between the front, rear, and end portions of the two box-sections A and B 75 is of greater width than the depth of the moisture-receiving chamber 15, and in the said space between the upright members of the two box-sections A and B intermediate of their opposing faces two spaced partitions 10 and 11 are located, extending from the bottom of the outer or casing section A to the top edge thereof, and the space between these two intermediate partitions 10 and 11 is provided with a packing of felt 12, sawdust, or 80 other non-heat-conducting material. By reason of the introduction of the intermediate packed section just described an outer air space or chamber 13 is formed between the intermediate packed section and the opposing 90 walls of the outer box-section A, and this air space or chamber 13 is closed at the top and at the bottom. Furthermore, an inner air space or chamber 14 is also provided corresponding to the outer air space or chamber 95 13; but the inner air space or chamber 14 at its lower end is in communication with the moisture-receiving chamber 15 at the bottom portion of the refrigerator. The inner air space or chamber 14 serves not only to keep 100

the inner box-section B cool; but any condensation which may occur at the outer face of the said inner box-section B is conducted downward by the said chamber or space 14 to the bottom chamber 15. Communication is established between the outside atmosphere and both of the air spaces or chambers 13 and 14 through the medium of tubes 16, which are passed through the front and the rear walls of the outer box-casing section A and through the intermediate packed section between the two box-sections, one end of each tube being in communication with the outside atmosphere and the other in communication with the inner chamber or air-circulating space 14. Each tube 16 is provided with apertures 17, so located as to permit the air passing through the tubes 16 to escape into the outer ventilating or air-receiving chamber 13, as is shown in Fig. 2. It will likewise be observed by reference to the same figure that suitable spacing-blocks 18 are employed at the top and at the bottom portions of the space between the two box-sections A and B, whereby to hold the intermediate packed section in position and to support the inner box-receiving section B.

A lining 19, of metal or other waterproof material, is provided for the bottom of the chamber 15, receiving the products of evaporation, and this lining is preferably made to extend upward a suitable distance along the inner wall of the outer or box-casing section A, as is clearly shown in Fig. 2, and the said inner wall of the outer or box section A is also provided above the upper edge of the metal lining 19 with a covering 20, of paper or other non-conductor, and the outer vertical wall of the inner box or receiving section B is provided with a similar covering 21, extending throughout the height of the vertical members of the said inner or receiving section B, as is also shown in Fig. 2.

The top C, provided for the body just described, is preferably made of hard wood, although any material may be employed, and includes an upper horizontal member 22 and a lower horizontal member 23, separated at the ends and back of the said cover by strips 24 and 25, forming between them an air-space 26. Air from the outside atmosphere is admitted to the space 26 through openings 27, which extend through the outer spacing-strips 24, as is shown by dotted lines in Fig. 2. The lower member 23 of the top is provided with one or more openings 28 in direct communication with the inner or receiving-box section B, and the upper portion of the said top above each opening 28 is provided with a recess 29, extending from a point at the rear of each opening 28 beyond the sides of the said opening and out to the front portion of the refrigerator, as is best shown in Fig. 1. A cover or lid 30 is adapted to slide in each of the recesses 29, and when the cover is in its rear position it closes the opening 28, over

which it has movement, and by drawing the cover or lid outward or forward the opening 28 to which it belongs is exposed, and access may be gained to the contents of the inner box-receiving section B below the opening 70 thus exposed. Each cover or lid 30 is preferably provided with an air-chamber 31 between its top and bottom surfaces, as is indicated in Fig. 2.

An opening is made in the bottom of the outer box-casing A, and an offtake-pipe 32 extends up into the said opening, being preferably provided with a bell-shaped or enlarged upper end. This offtake-pipe 32 is adapted to conduct away any fluid that may be collected in the lower or fluid-receiving chamber 15, which chamber, as stated, receives the products of evaporation or condensation from the air space or chamber 14, and any liquid which may collect in the inner receiving-box section B will find its escape through conducting-pipes 33, fitted in the bottom portion of said inner box-section, which conducting-pipes 33 are made to loosely enter the upper or enlarged portions of the offtake-pipes 32, as is illustrated in Fig. 2.

It will be observed that when the refrigerator is constructed as above set forth it is particularly adapted to preserve ice-cream or like substances in cans and that the cold air will be held in the refrigerator for a maximum of time; and that the refrigerator may be in a comparatively warm place without the heat materially raising the temperature within the refrigerator. Furthermore, it will be observed that the refrigerator is a particularly clean one and that all of the fluid which may be formed or contained in the refrigerator will find a ready and perfect exit, thus rendering the floor-space around the refrigerator dry, 105 which is a great advantage, as under the ordinary construction of refrigerators adapted for similar purposes such leakage occurs as to render the floor around the refrigerator exceedingly damp and injurious to health.

Having thus described my invention, I claim as new and desire to secure by Letters Patent—

1. A refrigerator, consisting of an outer box-section, an inner box-section smaller than the outer section and arranged therein with 115 its bottom spaced from the bottom of the outer section, the upper edges of the inner section being flush with the upper edges of the outer section, filled partitions in the spaces between the sides and ends of the sections, said partitions extending from the bottom of the outer section to the tops of said sections, and forming two chambers, the outer end of which is closed at top and bottom and the inner one closed at top and opening at the bottom into the space between the bottoms of said sections, open-ended tubes extending through the upper portion of the outer box-section and through the partitions, said tubes being apertured in the portions in the outer cham- 130

ber, an outlet-pipe leading from the bottom of each section, the pipe from the inner section extending into the pipe of the outer section, a top formed of two members having 5 between them an air-space which communicates with the outer air, the inner member of the top being apertured and the outer member recessed, and a sliding cover in the recess of the outer member of the top, as set forth.

10 2. A refrigerator, comprising an outer box-section, an inner box-section smaller than the outer section and arranged therein with its bottom spaced from the bottom of the said outer section, the upper end of the inner section being flush with the upper end of the outer section, filled partitions in the spaces between the sides and ends of the sections, said partitions extending from the bottom of the outer section to the tops of said sections, and forming 15 two chambers, the outer one of which is closed

20

at top and bottom and the inner one closed at top and opening at the bottom into the space between the bottoms of the sections, open-ended tubes extending through the upper portion of the outer section and through the partitions, said tubes being apertured in the portion in the outer chamber, and a cover for the said box-sections, said cover being formed of two members and spacing-strips forming an air-space between the members, one of the 25 spacing-strips being provided with openings leading into the air-space, as set forth.

In testimony whereof I have signed my name to this specification in the presence of two subscribing witnesses.

JOHN M. DOPPEL.
